UNITED STATES PATENT OFFICE

2,422,496

CONTROL DEVICE FOR DRAFT
REGULATORS

Clarence H. Morrow, Shaker Heights, Ohio, assignor to The Hotstream Heater Company, Cleveland, Ohio, a corporation of Ohio

Application January 4, 1945, Serial No. 571,239

3 Claims. (Cl. 236—45)

1

This invention relates to control or operating mechanism for a furnace draft stabilizing damper. It is an improvement upon the construction shown, described and claimed in Patent No. 2,381,437, for Control means for draft regulators, granted August 7, 1945, to Morris W. Crew and George A. Short, to which reference may be had for more complete understanding of certain of the features, if not completely described or shown here.

The control mechanism of said patent includes an operating member movable back and forth between two positions and driven in one direction by an electric motor of such form as to permit it to stall without injury, and in the opposite direction by suitable power means, such as a spring, said operating member being connected to the damper by disconnectible parts, all of the said parts being constructed and arranged so that with the mechanism in stand-by position and the motor deenergized, upon a thermostatic call for more heat, the motor is energized and drives the operating member in one direction to suddenly release the damper for normal stabilizing action during the period while the burner operates. When the demand for more or additional heat is satisfied, the motor circuit is deenergized and the operating member then is moved in the opposite direction by the power spring or other power source connected thereto, to slowly return the parts to their original position. Such mechanism includes speed reducing gearing driven by the motor and certain latch and holding devices.

The present invention has for its object to improve the mechanism of said patent by the inclusion in the operating connections between the motor and operating member of a floating coiled spring clutch so arranged that driving relation from the motor to the operating member, or vice versa, is permitted in one direction only, as will more fully appear hereinafter, for the purpose of distributing the wear on the speed reducing gears uniformly over their entire periphery, instead of limiting it to only a part of the teeth; which prevents gear clash and the impact of the momentum of the motor armature upon the gear teeth when the parts come to rest, with possible damage of the gears, as heretofore; and which avoids any possibility of bounce or return of the parts by reverse motion with consequent inaccuracy and possible faulty operation of the latching and disconnectible operating parts.

Further objects of the invention in part are obvious and in part will appear more in detail hereinafter.

2

In the drawings, which represent one suitable embodiment of the invention, Fig. 1 is a longitudinal sectional elevation through a furnace damper provided with my improved control, the front wall of the control casing being omitted to expose interior parts;

Fig. 2 is a similar view, showing the parts in another position;

Fig. 3 is a detail sectional view illustrating the speed reducing gear;

Fig. 4 is a sectional elevation on a larger scale, on the line 4—4, Figs. 1 and 3, showing the one-way clutch;

Fig. 5 is a detail end view from the right in Fig. 4; and

Fig. 6 is a sectional plan view on the line 6—6, Fig. 5.

Complete description of all of the parts of the mechanism is unnecessary, since reference may be had to said patent where that is desirable or necessary. It will suffice for this application to refer to many of the parts in a general way, as follows:

10 indicates a damper mounted for pivoting movement in a sleeve-like frame or housing 11 adapted for connection to a pipe leading from a furnace to the stack for controlling the flow of the check draft. Fig. 2 represents the stand-by position, in which the damper is held wide open, while Fig. 1 illustrates the position the parts assume upon a call for heat or more heat, the damper being free for normal stabilizing action.

Movement of the damper to one or the other of its positions is produced by an operating member 12, movable back and forth between two positions, as by reverse swinging motion about a pivot. The operating member shown, as in said patent, is a two-armed device, one arm of which, 13, is connected by disconnectible connections, indicated generally at 14, to a link 15 connected to the damper. The disconnectible connections cooperate with a pivoted latch 16. The other arm 17 of the operating member is connected to a suitable source of power, such as the tension spring 18.

The spring 18 always tends to move member 12 in the counterclockwise direction, Fig. 1. It may also be driven in the clockwise direction by an electric motor, marked generally 19, which drives the shaft 20, around the axis of which member 12 turns, by means of speed reducing gearing shown more or less diagrammatically in Fig. 3, and including a series of large gears 21 and small pinions 22, the drive being from the motor shaft 23 to

the first small pinion, then to a large gear, and so on to the final slow speed shaft 20.

With the arrangement described, as in the patent before referred to, the parts lie in the positions shown in Fig. 2 upon a stand-by. The electric motor is deenergized and the parts are held in the stand-by position by the tension of spring 18 and the engagement of pivot 24, about which link 15 swings, with the end of the slot 25 in said link.

Upon a call for heat or more heat by the thermostat (not shown) said thermostat closes the motor circuit and the motor immediately begins to rotate in a direction to turn member 12 in the clockwise direction. Practically immediately, the disconnectible connections separate and the damper is released and moves promptly to its position shown in Fig. 1, for normal stabilizing action. The motor continues to rotate until finally the second arm of member 12, to which spring 18 is secured, engages the stop 26, with the parts in the position shown in Fig. 1. There they remain until the call for heat is satisfied, whereupon the motor circuit is opened. The motor, of course, is of the ordinary clock motor type, capable of being stalled without injury, as described in said patent.

When the motor circuit is opened spring 18 begins to turn member 12 in the opposite direction, also driving the rotor of the electric motor reversely through the speed reducing gearing, the latter serving to retard motion of member 12 and delay the completion of motion of the damper to the stand-by position shown in Fig. 2.

According to the present invention, for purposes and advantages to be later referred to I introduce into the driving connections between the electric motor and operating member 12 a one-way or overrunning clutch device or mechanism, of special form, and so arranged, that driving effect may be produced from the speed reducing gearing to member 12, or reversely from member 12 to the speed reducing gearing, but in each case only in one direction.

The mechanism is relatively small, space being at a premium in and around the space at the hub of lever 12. Accordingly I provide a very compact and improved spring clutch which may be made and operatively assembled with the other parts by simple operations and at low cost.

The drawings show for the purpose one suitable form of spring clutch illustrated in detail in Figs. 4, 5 and 6. As illustrated the end of the slow motion shaft 20 is left plain, except for a small diameter cross hole 30 to receive a securing cotter pin 31. Around the shaft is sleeved a coiled clutch spring 32 having its inner end plain, at 33, and its outer end bent tangentially to form an operating arm 34.

Spring 32 is housed or enclosed in the cavity 35 of a sleeve-like hub 36 permanently fastened to and forming the hub of lever 12, the outer end of said hub being provided with a slot 37 to receive the operating arm 34. Cavity 35 at its inner end is slightly enlarged, at 38, to house the plain inner end of the spring clutch and avoid any sticking effect such as might be caused by a rough end of the spring riding on metal of the hub.

The turns of the coil spring are fairly close together and said coil has such internal diameter that it is a snug fit upon shaft 20. In other words all of its turns at all times are in actual contact with a light frictional drag upon the shaft surface. The direction of twist, right or left, is such that when the hub is held stationary, as in Fig. 5,

clockwise rotation of the slow speed shaft 20 tends to close or wind the coils more tightly about the shaft, while shaft rotation in the opposite direction tends to open up the coils and free them from the shaft. Thus, the spring serves as a one-way driving clutch, permitting driving effect from shaft 20 to the hub, or vice versa, but in each case in one direction only.

With the construction described, assuming the 10 parts in the stand-by position Fig. 2, and that the thermostat has called for heat or more heat and thus has closed the motor circuit, the motor begins to turn in the clockwise direction Fig. 1. Practically immediately the disconnectible parts 15 are disconnected, as in said patent, and the damper promptly moves to the position shown in Fig. 1, for normal stabilizing action. The motor continues to operate, turning shaft 20 and driving hub 36 through the spring clutch in the clockwise 20 direction Fig. 5, and turning member 12 until it engages the stop 26. Thereupon movement of member 12 stops, and through the clutch fully prevents further advance or rotation of the motor rotor and reducing gear. The parts are held in 25 this position, with the motor stalled, so long as the motor is energized.

When the call for heat is satisfied, the thermostat opens the motor circuit, as before described, and the spring 18 becomes the operating power 30 source, exerting its effect through member 12 upon the hub 36, driving it in the counterclockwise direction Fig. 5 and through the clutch spring also turning shaft 20, the reducing gearing, and the motor rotor in the reverse direction from 35 before. This operation continues until finally the parts reach the position shown in Fig. 2, with the pin 24 at the end of the slot 25 and forming a positive stop for motion of member 12. However, the one-way clutch now permits the shaft 20, speed reducing gearing and the motor rotor to 40 continue to rotate until the force and tendency to move have been expended in friction. The parts are then ready for the next cycle of operations.

45 The mechanism avoids any possible rebound effect as the parts reach the stand-by position of Fig. 2. Heretofore, when the shaft 20 has been positively connected to member 12, so that the two parts always rotate together, when the 50 parts reach the stand-by position, driven by the force of spring 18, at the moment of impact of the pivot pin 24 with the end of the slot 25, the heavy force of the rotating motor armature causes it to rebound, as it were, so that in actual 55 practice it may rotate reversely as much as 10 or 15 revolutions. This rebound effect sometimes has been sufficient to unlatch the disconnectible parts and permit false operation or motion of the damper, undesirably, to its position for normal 60 stabilizing action, even though at times the latch 16 has been given increased depth to overcome the difficulty. Such rebound is absolutely prevented by the use of the one-way clutch described, as will be readily understood, and avoids 65 any necessity of specially forming the latch parts.

The coil spring is a very simple form of clutch, requiring only enlargement of the central opening 70 in the hub and the provision of the cross slot for its introduction into the device.

The construction described is simple, durable, effective, and not liable to get out of order, and may be applied both to new control devices or 75 as replacement parts for those already in use.

Further advantages of the invention will be apparent to those skilled in the art.

What I claim is:

1. Apparatus of the character described, comprising an electric motor, speed reducing gearing driven by the motor and including a slow running shaft member, an operating device having a hub member surrounding the shaft member, power means connected to the operating device to positively turn it about the shaft axis, and a coil spring surrounding and closely fitting the shaft, one end of said spring being free and the other end being connected to one of said members, said spring serving as a one-way clutch between said members permitting drive through said spring of said operating device by said motor in one direction only or of the motor by said operating device in the opposite direction only.

2. Furnace damper control mechanism of the character described, comprising, in combination, a damper, an operating device movable back and forth and having a disconnectible connection to said damper, an electric motor, speed reducing gearing driven thereby and including a slow running shaft, and a coil spring surrounding and closely fitting said shaft, one end of said spring being free and the other end being fastened to said operating device and power means effective directly upon said operating device and tending to move it reversely to its movement by the motor, said spring serving as a one-way clutch for establishing driving connection through it between the motor and operating device.

3. Control means for a furnace draft stabilizing damper, comprising an electric motor adapted while energized to be stalled without injury thereto, means operatively connecting said motor and damper and having stand-by and damper release positions, said connecting means including speed reducing gearing connected to the motor rotor and including a slow running shaft, an operating device connected to the damper and movable back and forth and having a hollow hub surrounding said shaft, power means effective upon said device and tending to move it reversely to its movement by the motor, and a coiled spring surrounding the shaft and housed within the hollow hub and having one end connected to said hub and the other end free, said spring serving as a one-way clutch between said reduction gearing and operating device to permit drive by either to the other in one direction only.
